W. H. MYERS.
CORNER BRACE FOR CASES AND THE LIKE.
APPLICATION FILED JULY 22, 1919.

Patented Oct. 19, 1920.

Inventor
William H. Myers,

UNITED STATES PATENT OFFICE.

WILLIAM H. MYERS, OF NEW YORK, N. Y.

CORNER-BRACE FOR CASES AND THE LIKE.

1,356,391.

Specification of Letters Patent.

Patented Oct. 19, 1920.

Application filed July 22, 1919. Serial No. 312,595.

To all whom it may concern:

Be it known that I, WILLIAM H. MYERS, a citizen of the United States, residing at New York, in the county of New York and

5 State of New York, have invented certain new and useful Improvements in Corner-Braces for Cases and the like; and I do hereby declare the following to be a full, clear, and exact description of the invention, such as will enable others skilled in the art to which it appertains to make and use the same.

This invention relates to improvements in corner braces for cases and the like wherein 15 angular members are provided which embrace the corners and sides of a case.

The object of this invention is to provide corner members which are adapted to distribute the force of the concussion due to 20 sudden impact over a considerable area of the sides of a case, thereby removing this force of impact from direct contact with the corners of a case.

A further object is to provide a device of 25 the character described constructed with three angularly extending and angularly formed arms extending, from a common point of intersection, in three directions at angles approximately less than 90° to one 30 another for the purpose of distributing the force of impact, at the corner, over a considerable area of each side to which the end of each arm is secured.

These objects are attained by means of 35 the device herein described and illustrated in the accompanying drawings in which—

Figure 1 is a perspective view of the corner brace attached to a corner of a case;

Fig. 2 is an end view in elevation, and

40 Fig. 3 is a sectional elevation taken on line 3—3 of Fig. 2.

Referring in detail to the parts, 1 designates an angular body portion provided with angular arms 2 having attachment portions 45 3 formed thereon. The angular arms are so arranged that the dihedral angle, contained between the planes embracing the two corresponding side members of the angular arms, is less than a right angle or 90° or is less 50 than the angle formed by the sides of a case, as clearly shown by the dotted lines 4 in Fig. 3 and by the sides of a case 5 shown in Fig. 2.

The device is securely attached to the case 55 5 by means of any suitable screws or nails as at 6, and the fastening or attaching por-

tion 3 is bent away from the line of the angularly formed arms 2 so that its plane coincides with the plane of the side of the

60

It is obvious that a blow due to impact upon the nose or corner of the body portion will be received by the angular arms and the force of the blow carried by the arms to the connecting or attaching portion away from 65 the corner of the case, thereby saving the corner from premature destruction and preserving the case for maximum length of utility.

In Fig. 1, the dotted lines 7 show a modified form wherein the angular arms are replaced by side member embraced within the dotted lines and the corner edges of the device.

It is obvious, however, that various other 75 modifications may be embodied without departing from the spirit of this invention. It will therefore be understood that this invention is not limited to the particular construction shown.

80 What is claimed is:

1. A corner brace for cases and the like comprising an angular body portion having integrally formed arms extending therefrom, each arm being angular in cross-section for 85 embracing a corner edge of the case, said arms and body portion co-operating to distribute the force of impact at the corner away from the apex and to the sides of the case.

90

2. A corner brace for cases and the like comprising an angular body portion having integrally formed arms extending therefrom, each arm being angular in cross-section for 95 embracing a corner edge of the case, said arms engaging and being secured to the case at their outer ends, and disengaged from said case for the remainder of their length so as to distribute the force of impact at the corner away from the apex and to the 100 sides of the case.

3. A corner brace for cases and the like comprising a plurality of integrally formed arms emanating from a common source and forming a polyhedral angle less than the 105 polyhedral angle at the apex of the case over which said brace is applied whereby said arms will stand away from the case near their integrally connected ends and will engage the case at their free ends.

110

In testimony whereof I affix my signature.
WILLIAM H. MYERS.
